DRAWER HANDLE

James D. Floria, Milwaukee, Wis., assignor to Hamilton Manufacturing Company, Two Rivers, Wis., a corporation of Wisconsin

Application August 10, 1956, Serial No. 42,574

Term of patent 14 years

(Cl. D10—8)

Fig. 1

Fig. 2

Fig. 3

Fig. 4

Figure 1 is a front elevational view of a drawer handle showing my new design;

Figure 2 is a side view thereof;

Figure 3 is a vertical cross-section taken on the line 3-3 of Fig. 2; and

Figure 4 is a horizontal section taken on the line 4-4 of Fig. 2.

I claim:

The ornamental design for a drawer handle, substantially as shown.
